CLAIM

The ornamental design for a humidifier reservoir for positive airway pressure delivery console, as shown and described.

DESCRIPTION

FIG. 1 is a perspective view, from the front, left corner, of a humidifier reservoir for positive airway pressure delivery console showing an embodiment according to our new ornamental design;

FIG. 2 is right side view thereof;

FIG. 3 is a left side view thereof;

FIG. 4 is a top view thereof;

FIG. 5 is a bottom view thereof;

FIG. 6 is a front view thereof;

FIG. 7 is a rear view thereof;

FIG. 8 is another perspective view thereof;

FIG. 9 is a perspective view, from the front, left corner, of a humidifier reservoir for positive airway pressure delivery console showing an embodiment according to our new ornamental design;

FIG. 10 is right side view thereof;

FIG. 11 is a left side view thereof;

FIG. 12 is a top view thereof;

FIG. 13 is a bottom view thereof;

FIG. 14 is a front view thereof;

FIG. 15 is a rear view thereof; and,

FIG. 16 is another perspective view thereof.

In the drawings, the broken lines are for the purpose of illustrating environment only and form no part of the claimed design.
